UNITED STATES PATENT OFFICE.

WILLIAM A. EMERSON, OF LEOMINSTER, MASSACHUSETTS.

COMBINED BLACKBOARD AND DRAWING-CASE.

SPECIFICATION forming part of Letters Patent No. 329,300, dated October 27, 1885.

Application filed January 12, 1885. Serial No. 152,627. (No model.)

To all whom it may concern:

Be it known that I, WILLIAM A. EMERSON, a citizen of the United States, residing at Leominster, in the county of Worcester and State 5 of Massachusetts, have invented new and useful Improvements in a Combined Drawing-Case and Blackboard, of which the following is a specification.

This invention relates to improvements in 10 art blackboards and drawing-cases combined, the object being to provide an improved drawing-case for students, having combined therewith a pivoted blackboard, all arranged to be employed, as hereinafter set forth, for 15 facilitating the acquirement of the art of drawing, and particularly so from memory.

In the drawings forming part of this specification, Figure 1 is a front elevation, and Fig. 6 is a perspective view, of a combined 20 art blackboard and drawing-case constructed according to my invention. Fig. 2 is a longitudinal section on the line xx , Fig. 1. Fig. 3 is a detail view. Figs. 4 and 5 illustrate 25 details of a modified manner of pinning the blackboard to the case. Fig. 7 is a perspective view of the drawing-case, showing the blackboard turned up.

In the drawings, A is the drawing-case, consisting of the flat bottom a' , having the side 30 rails, m , secured one on either edge thereof, the upright end pieces b' and end piece b , and the overhanging piece A' , secured to the upper edges of the pieces b' , thereby forming a chamber at one end of the case. At the 35 rear side of said chamber, lying transversely across the case and secured to the latter, is a chalk and crayon rest, f . A shaft, c , whose ends have bearings in the end pieces b' , has attached thereto by arms, as shown, a rotating design-board, B, the latter being of 40 such length and size as to permit of its being rotated back and forth within said chamber by turning shaft c , or by giving to the latter a reciprocating rotary motion, and said design-board B is adapted, when rolled forward, to 45 close the front side of said chamber, as in Fig. 6, lying in an inclined position, its outer face having temporarily secured thereon designs 8 8, of any desired description, of which 50 the student is to make a copy or copies. The blackboard i has the rails h secured to its opposite edges, and is fitted to slide back and

forth between the side rails, m , of the case A, its position when pushed quite inward being shown in Figs. 2 and 6. The outer sides of 55 the rails h , next to the rails m , have each a groove, z , therein extending from near the rear end to about the center of the rail. A pin, n , passes through each rail m , the end of which enters said groove z in the rail h . 6c A pin, o , is placed in one of the rails h , and a pin, o^2 , in the rail on the opposite edge of the blackboard, and in a line with said pins on shaft c are placed the pins e and d , Fig. 3 showing the relative positions of said pins o 65 and d when the blackboard is drawn out far enough to bring pin o in front of shaft c , and the position of pin d is there shown directly behind the former pin, o . In said last-named figure is also shown the positions of the pins o^2 and e with the blackboard in the above-named position.

The apparatus is employed and its operation is as follows: Referring now to Fig. 6, the designs 8 8, one or several, are attached to the 75 face of board B temporarily, and subject to any desired change, and the student is required to copy said designs upon paper placed on the side of the blackboard i in front of the designs. After the student has made said copies it is 80 desirable that the originals be removed from his sight, and that he be required to redraw said designs from memory, and to bring the blackboard to proper position to draw on, and at the same time carry said designs beyond 85 the view of the student, as shown in Fig. 7, the blackboard i is drawn forward, causing pin o^2 (see Fig. 2) to strike pin e , and, rolling shaft c , turn the board B over to the position there shown in dotted lines, and the blackboard, 9c being drawn out until it is brought to a stop by the pins n , is then turned up against the front of the higher part of the case A, as shown in Fig. 7, and bringing its blacked face before the pupil in convenient position to be drawn upon. To restore the parts to the position shown in Fig. 6, the blackboard is swung forward to a flat position, and being pushed into the case pin o moves against pin d in shaft c , rolling the latter and throwing board B forward again. 95 100

By reference to Figs. 4 and 5 it will be seen, as there illustrated, that instead of grooving the rails h of the blackboard the rails m of the

case may be grooved, and a pin, 5, to engage in the groove z^2 , be placed in the rail h , instead of in the rails m , thereby furnishing an equivalent pivotal and sliding connection between the blackboard and case A to that shown in the other figures of the drawings.

What I claim as my invention is—

1. A drawing - case, substantially as described, provided with a reciprocally-rotating design-board connected to a shaft in said case, and with a blackboard, substantially as described, having a pivotal and sliding connection with the case and adapted to engage with said shaft, combined and operating substantially as set forth.
2. A drawing - case, substantially as described, having an elevated chamber thereon, a shaft hung in the latter, a design-board attached to said shaft, and a blackboard adapted

to slide and swing on said case, and provided with means, substantially as described, for engaging with said shaft when moving under the latter, combined and operating substantially as set forth.

3. In combination, the sliding pivoted board i and the case A, having an elevated chamber at the rear end thereof, forming a support to hold said board in an upwardly-inclined position, substantially as set forth.

4. In combination, the case A, the shaft c , provided with the pins d and e , the design-board B, and the blackboard i , provided with the pins $o o^2$, and adapted to slide in the case, substantially as shown and described.

WILLIAM A. EMERSON.
